UNITED STATES PATENT OFFICE.

GEORGE L. HALL, OF MELROSE, MASSACHUSETTS.

MINIATURE-STAGE-LIGHTING SYSTEM.

Application filed November 23, 1926. Serial No. 150,361.

This invention relates to a miniature theatre stage-lighting system and to a miniature stage with which said lighting system may be used by scenic artists, teachers and 5 students in art schools and the like, to obtain on a miniature scale in the studio or school the lighting and color effects it is desired to produce on the scenery of the stage of a regular or full-size theatre.

10 To this end the lighting system is provided with a miniature switchboard mounted on a miniature stand capable of being carried by hand, and provided with a panel having mounted thereon a plurality of rows 15 of miniature rheostats of relatively low resistance, each of which rows of rheostats is connected in circuit with a plurality of miniature incandescent lamps of low voltage and of different colors which may and preferably will be mounted on a reflector to form 20 a lighting unit, which is capable of being placed in different positions with relation to the miniature stage.

The miniature stage may be a permanent 25 structure, or, as preferred, it may be made as will be described so as to be knocked down into compact form for transportation by hand, and which can be set up in a minimum time to produce in the studio or classroom a practically complete miniature theatre stage on which the lighting and color 30 effects may be produced and quickly and easily changed to produce the desired color effects on the scenery.

35 The panel of the portable switchboard may also be provided with one or more individual rheostats, which are connected in circuit with lighting units having individual, miniature lamps to obtain spotlight and like 40 lighting effects.

The portable miniature switchboard may and preferably will be provided with means for supporting the portable lamps and their 45 circuit wires, when the said lamps are not in use.

These and other features of this invention will be pointed out in the claims at the end of this specification.

Fig. 1 is a front elevation of the portable 50 stage;

Fig. 2, a plan view of Fig. 1;

Fig. 3, a side elevation of the stage shown in Fig. 1, looking toward the right;

Fig. 4, a detail of a portion of the stage with one of the border-lighting units suspended therefrom;

Fig. 5, a longitudinal section of the border-lighting unit shown in Figs. 2, 3 and 4;

Fig. 6, a detail in cross-section of the foot-lighting unit shown in Fig. 3;

Fig. 7, a plan of the foot-lighting unit shown in Fig. 6;

Fig. 8, a front elevation of the portable miniature switchboard with which lights shown in Figs. 2 to 7 are connected;

Fig. 9, a side elevation of the switchboard shown in Fig. 8, and

Fig. 10, a detail of one of the spotlights shown in Fig. 3.

In Figs. 1 to 4 is illustrated a portable 70 miniature theatre stage, which is capable of being transported by hand and which is preferably of the construction as will now be described.

The stage is provided with a front upright 75 wall 10 having a proscenium-arch 12, a rear upright wall 13 detachably connected with the front wall 10 by top beams or cross members 14 and by bottom members 15, which constitute part of the stage floor.

The upright front and rear walls 10, 13 and the floor members 15 may be of any suitable material which is light yet strong, such as relatively thick paper board. The top cross members or beams 14 may and preferably will be made of metal, such as light angle iron, like that used in meccano constructions. These beams are detachably secured to the front and rear walls 10, 13 by screws 16 and nuts 17, the screws 16 being 90 extended through end flanges 18 of the beams, as clearly shown in Figs. 3 and 4. The floor members 15 are hinged at one end to one of the upright walls, and are detachably secured at their opposite ends to the other of said walls.

In the present instance, the floor members 15 are hinged to the front wall 10 by hinges having one leaf 20 secured to the wall 10 by a screw 21 and a nut 22, and the other leaf 23 being secured to a floor member by the screw 24 and the nut 25. The opposite end

of each floor member 15 is secured to the horizontal member 26 of an angle iron by a screw 27 and a nut 28, and the vertical member 29 of said angle iron is fastened to the upright rear wall 13 by a screw 30 and a nut 31.

The front wall 10 may and preferably will also be tied to the rear wall 13 by inclined braces, preferably extensible or adjustable 10 by being made in two pieces 32, 33 which are secured together by screws 34 and nuts 35, the screws being extended through suitable slots (not shown) in said pieces.

Each brace 32, 33 is provided at its outer 15 ends with flanges or angular extensions 37, 38 through which the screws 27, 39 are passed and which are fastened to the rear wall 13 by the nut 28 and to the front wall 10 by the nut 40 (see Fig. 3).

20 It will thus be observed that the front and rear walls are connected together at their top and bottom and form a miniature portable stage which is capable of being set upon a desk, table or like support, represented by 25 the line 41 in Fig. 3, and which is capable of being knocked down and assembled together in a compact condition for transportation by hand or for shipment.

The floor members 15 support a center 30 floor section 42 of glass, which is preferably of greater length than the proscenium-arch and whose opposite sides rest upon the floor members 15.

The space 43 below the floor of the stage 35 is rendered accessible by providing the front upright wall 10 with movable doors 45 pivotally secured to the stationary side portions of the front wall by hinges 46.

The cross top beams 14 have their vertical 40 members 47 provided with openings 48 for the reception of rods 49, which constitute overhead supports for the drops or scenery 50, only one of which is shown in Figs. 2 and 3, and for the overhead or border lights 51 used to illuminate the drops from above.

The overhead supporting rods 49 are capable of being adjusted with relation to the drops or scenery 50 by inserting them in different openings 48 in the cross beams 50 14, and are retained in their adjusted positions by a head 52 on one end of each rod and a nut 53 on the other end of said rod.

In Fig. 2, six overhead supports or rods 49 are shown, and each pair of these rods 55 may be used to support a drop 50 and a border-lighting unit 51 co-operating therewith.

The border-lighting unit 51 may and preferably will be made as herein represented 60 (see Figs. 4 and 5), and comprises a substantially trough-shaped reflector 54 of a length sufficient to support a plurality of sets of different colored incandescent lamps of low voltage.

65 In the present instance, each border-light-

ing unit 51 is provided as shown in Fig. 5 with three sets of lamps, each set comprising four lamps of different colors, which are represented in Fig. 5 as red, yellow, green and blue, which are respectively 70 marked 56, 57, 58, 59.

As shown, each lamp is screwed into a threaded socket 60 secured to a partition wall 61 of the reflector, which wall forms a common return for the circuits in which the 75 lamps are included and to which a common return wire or conductor 62 (see Fig. 5) is soldered or otherwise electrically connected.

The metal partition wall 61 of the reflector forms a chamber 63 with the upper 80 part of the reflector and in this chamber are located the inlet wires 64 for the different lamps of the series, which inlet wires are connected with terminals 65 supported by arms or brackets 66 secured to the partition 85 wall 61 of the reflector. The arms 66 are suitably insulated from the terminals, as indicated by the heavy black lines 67.

The reflector 54 is designed to be detachably suspended from one of the supporting 90 rods 49, which may be effected as shown by means of a wire loop 70 attached to the reflector and engaging a hook 71 mounted on one of the rods 49 (see Fig. 4).

The lamps of the border-lighting unit are 95 controlled from a portable switchboard, which is capable of being transported by hand and of being placed in proximity to the miniature stage.

In the present instance, a preferred construction of switchboard is shown in Figs. 8 and 9, and comprises a panel 72 of insulating material, such as hard rubber or bakelite, which is secured to a metal frame comprising horizontal bars 73 and upright 105 rods 74.

The horizontal bars 73 are provided at one end with angle irons 75 to which latter the lower end of the panel 72 is secured by screws 76 and nuts 77. The panel 72 is detachably secured at its upper end by nuts 78 to the bent upper ends of the rods 74, which ends are extended through the panel from the rear to the front side thereof.

The lower ends of the rods 74 are extended 115 through the rear end of the horizontal bars 73 and secured thereto by nuts 79, 80, the nut 80 being provided with a rounded outer surface to constitute a foot for the portable switchboard, and the front end of the horizontal bar being provided with a similar nut 81 which forms a foot for the switchboard, and which co-operates with a screw 82 to fasten the angle iron 75 to the horizontal bar 73.

The panel 72, upright rods 74 and horizontal bars 73 co-operate to form a substantially triangular frame, which is light, portable and relatively inexpensive. The panel 72 has mounted upon it a plurality of hori- 120 125 130

5 horizontal rows of rheostats 85 which are located on the rear side of the panel and attached thereto, and which have their shafts 96 extended through the panel and provided with handles or knobs 87 for turning the same.

10 These rheostats have a relatively low resistance value, preferably about thirty ohms, and are like those now commonly used in 15 radio receiving sets.

15 The rear upright rods 74 may and preferably will be provided with one or more supporting members, represented as hooks 89, upon which the border and other lighting 20 units used for lighting the miniature stage, may be supported when not in use, as represented in Fig. 9.

25 In the present instance, the panel 72 is provided with three horizontal rows of rheostats; those of the uppermost rows, marked "Border" in Fig. 8, being designed to control the border-lighting units; those marked "Footlights" being designed to control the footlights, and those marked "Spotlights" 30 being designed to control the spotlights.

35 In Fig. 3, two footlighting units are shown as located in the space 43 below the floor of the miniature stage. These footlighting units are represented in Figs. 6 and 7, and 40 each comprises a reflector 90 provided with a plurality of sockets 91 for the reception of a plurality of sets of lamps 92, herein shown in Fig. 7 as composed of four sets of three each, which are electrically connected with the rheostats in the second horizontal row on 45 the panel.

50 The reflectors 90 are provided with a flat surface 93 which is designed to rest on the desk or other support upon which the miniature stage is placed.

55 The reflectors of the footlighting units are arranged to throw light upwardly through the glass floor section 42, and one lighting unit may be located near the front wall 10 to obtain the lighting effect of the usual footlights in the regular theatre, and the other may be located near the rear wall 13 so as to throw the light upwardly on said rear wall or upon the drop or scenery, as 60 represented in Fig. 3.

65 The footlighting unit or units represented in Fig. 3 are designed to be supported when not in use by the horizontal bars of the portable switchboard, as represented in Fig. 9, 55 wherein one footlighting unit is shown.

70 The third horizontal row of rheostats on the panel 72 is designed to control lighting units having individual spotlights, which are represented in Fig. 10, and comprise a reflector 94 provided with a miniature lamp, not shown, but like those illustrated in Figs. 5 and 6, and also provided with a suitable rim or frame having members 95, 96 between which a piece of colored celluloid or like ma-

75 terial 97 is placed, to give the particular color effect desired.

80 A plurality of these spotlight-lighting units may be pivotally mounted upon a portable frame or miniature light bridge, comprising a top bar or member 98, and upright side bars or members 99, represented by dotted lines in Figs. 1 and 2, and one side bar of which is shown in full lines in Fig. 3.

85 Only one spotlight unit is shown in Fig. 75 3, which is pivotally secured to a bracket adapted to be detachably fastened on the top member 98 of the light bridge, but it will be understood that additional spotlights 94 are and may be pivotally connected with brackets 100 90 which are detachably secured to the top member 98 and also with the upright side members 99 of the light bridge.

95 The spotlight units have their wires connected with the rheostats in the third horizontal row on the panel, and when not in use may be hung upon the hooks 89 or otherwise supported by the switchboard frame.

100 The panel of the switchboard may be provided with a miniature lamp 101 for lighting the front of the board.

105 In the present instance, the panel 72 is shown as provided with three horizontal rows of rheostats, each row comprising four rheostats, one for each color of lamp, and 95 when a lighting unit, such as the border and foot lights, is provided with a plurality of sets or groups of lamps, as represented by the lighting units, shown in Figs. 5 and 7, the lamps of the same color in said lighting 100 unit are electrically connected with a single rheostat in said horizontal row.

110 As represented in Fig. 5, the lighting unit is provided with three groups or sets of miniature lamps, each set or group of lamps 105 comprising lamps of four different colors, to wit: red, yellow, green and blue, and the lamps of the same color are connected in circuit with a suitable source of current supply through a single rheostat, and to make this 110 clear, the rheostats on the panel 72 have had applied to them, the color of the lamp which they control.

115 In the present instance only three horizontal rows of rheostats are represented on the panel 72, which number of rows is deemed sufficient to illustrate the invention, but it will be understood that the panel 72 may be provided with additional rows of rheostats, if necessary, to obtain the desired 120 lighting effect.

125 It will be further understood that the different lighting units are connected with the rheostats on the panel 72 by the wires 62, 64 assembled in the form of cables 105, portions of which are shown in Figs. 2, 3, 5 and 7, so that the lighting units are directly and permanently connected with the rheostats of

the switchboard and are capable of being assembled thereon to be portable therewith when not in use, and to be removed therefrom and placed in different positions with 5 relation to the miniature stage when in use, whereby different lighting effects upon the miniature stage may be obtained in order to determine the best lighting effect for a particular setting of the stage, and when the 10 best lighting effect on the miniature stage is obtained, the same effect may be obtained in the regular theatre without further experimentation with the lights of the regular theatre.

15 The portable switchboard may be provided with a handle 106 attached to the panel 72, by means of which it can be conveniently carried in one hand of the person transporting the same.

20 The miniature portable switchboard having the miniature or low voltage lamps, preferably six volts, may be used with safety and to advantage with a miniature stage which is capable of being knocked 25 down and assembled in compact form, as, for instance, when used by different scenic artists, but it is not desired to limit the invention in this respect, as the miniature switchboard and its connected lighting units 30 portable therewith, may be used in relatively large studios, art schools and like places, with miniature stages of different designs and structures, which may be more or less of a permanent character and not 35 capable of being knocked down.

One embodiment of the invention, which may be preferred, is herein shown, but it is not desired to limit the invention to the particular construction shown.

40 What is claimed is:

1. In a portable miniature stage-lighting system, in combination, a portable miniature switchboard provided with a panel having thereon a plurality of relatively low resistance rheostats, a plurality of lighting units governed by said rheostats, some of said lighting units comprising a reflector and a plurality of sets of relatively low voltage lamps carried by said reflector, the lamps 45 of each set being capable of giving different colored lights, and flexible conductors connecting the lamps of the same color of the different sets of lamps to a single rheostat on said panel, said flexible conductors being 50 of substantial length to permit the lighting units to be located a substantial distance away from the switchboard when in use and to enable said lighting units to be assembled on the switchboard to be transported there- 55 with when not in use.

60 2. In a portable miniature stage-lighting system, in combination, a portable miniature switchboard comprising a substantially triangular frame having a panel forming 65 one side of said frame and provided with a

plurality of relatively low resistance rheostats arranged in rows, a plurality of lighting units co-operating with said rheostats to be controlled thereby, some of said lighting units comprising a reflector having a 70 plurality of sets of lamps of different colors, with the colored lamps in each set corresponding in number to the rheostats in a given row on said panel, and flexible conductors of substantial length connecting the 75 lamps of the same color in the different sets of lamps of one lighting unit with the same rheostat in said given row of rheostats.

3. In a portable miniature stage-lighting system, in combination, a portable miniature 80 switchboard comprising a frame portable by hand, a panel secured to said frame and provided with a plurality of relatively low resistance rheostats mounted thereon, a lighting unit comprising a reflector and a plurality of relatively low voltage lamps of different colors co-operating with said reflector and arranged in sets, and flexible conductors connecting said lamps with said rheostats in a manner to enable a single 90 rheostat to control the same colored lamp of all the sets of lamps, said flexible conductors being of substantial length to enable the lighting unit to be located a substantial distance from said switchboard and 95 being connected with said rheostats and lighting unit to enable the latter to be supported by said frame and transported therewith when not in use.

4. In a portable miniature stage-lighting 100 system, in combination, a portable miniature switchboard having mounted thereon a plurality of groups of relatively low resistance rheostats, a plurality of lighting units of relatively low voltage movable with relation 105 to said portable switchboard and capable of giving different colored lighting effects, and flexible conductors connecting said lighting units with said rheostats and of sufficient length to enable the lighting units to be 110 placed at different distances from said switchboard when in use.

5. In a miniature stage-lighting system, in combination, a miniature switchboard having mounted thereon a plurality of groups of relatively low resistance rheostats, a plurality of lighting units of relatively low voltage movable with relation to said switchboard and capable of giving different colored lighting effects, and flexible conductors directly connecting said lighting units with said rheostats to enable the lighting units to be supported by the switchboard when not in use, and of sufficient length to enable the lighting units to be placed at different distances from said switchboard when in use.

6. The combination with a miniature stage, of a miniature lighting system therefor comprising a miniature switchboard 130

having mounted thereon a plurality of groups of relatively low resistance rheostats, and a plurality of lighting units of relatively low voltage movable with relation to

5 the miniature stage and capable of being placed in different positions with relation thereto to obtain different lighting effects

on said stage and flexibly connected with said rheostats to be controlled by the latter while permitting movement of the lighting 10 units with relation to said stage.

In testimony whereof, I have signed my name to this specification.

GEORGE L. HALL.
